UNITED STATES PATENT OFFICE.

ARTHUR L. SMITH, OF LOS ANGELES, CALIFORNIA, ASSIGNOR TO NATIONAL AUTOMATIC MACHINE COMPANY, OF LOS ANGELES, CALIFORNIA, A CORPORATION OF CALIFORNIA.

COIN-CONTROLLED VENDING APPARATUS.

No. 893,203.

Specification of Letters Patent. Patented July 14, 1908.

Application filed September 24, 1906. Serial No. 336,010.

To all whom it may concern:

Be it known that I, ARTHUR L. SMITH, a citizen of the United States, residing at Los Angeles, in the county of Los Angeles and State of California, have invented new and useful Improvements in Coin - Controlled Vending Apparatus, of which the following is a specification.

My invention relates to that class of vending machines in which the coin inserted, temporarily forms a part of the vending operating mechanism and an object thereof is to provide a machine that will accurately and automatically deliver the goods vended by the apparatus.

Another object is to provide a machine in which the coin controlled mechanism is so arranged that it will not deliver merchandise unless a coin of the proper size and denomination is placed therein.

Another object is to provide a machine in which the coin controlled mechanism is so arranged that when an improper coin or blank is inserted that it will reject and return it.

Another object is to provide a machine whereby only the proper amount of merchandise will be delivered at one operation.

A further object is to provide a machine which is simple in construction, positive in operation and embodying economy in the cost of manufacture.

I accomplish these objects by means of the device described herein and illustrated in the accompanying drawings in which:

Figure 1.— is a perspective view of my complete machine. Fig. 2.— is a perspective view of my machine with the outer casting removed. Fig. 3.— is an enlarged longitudinal section taken on the line 3—3 of Fig. 2 looking in the direction indicated by the arrows.

In the drawings I have shown the vending apparatus as adapted especially for the vending of lead pencils, but of course I do not limit myself to such use as articles, such as cigars, cigarettes and like structures may be vended equally as well.

Referring to the drawings 5 indicates a rectangular frame open at the top and having an inclined bottom or chute 6. Vertically mounted on the frame 5 and rigidly secured thereto at the back thereof is a pencil hopper 7, preferably constructed of metal and the width and thickness is approximately the

same as the length and diameter of the pencils which lie on top of each other. This hopper may be of any desired height so as to hold a greater or less quantity of pencils. Rigidly secured to the front side of the hopper are a plurality of downwardly projecting lugs 8 which are provided on their lower ends with cylindrical supporting pins 9 which extend across the discharge end of the hopper and on which the column of pencils rest. The rear wall of this hopper terminates above the supporting pins 9 a distance slightly greater than the diameter of a pencil, so as to allow sufficient space for its ejection. Rotatively mounted in the frame 5 at a distance slightly to the rear of the discharge end of the hopper 70 and extending transversely thereof, is a cylindrical shaft 10 to which are rigidly secured a plurality of star wheels 11, which operate on the turnstile principle. These wheels consist of a number of arms 12 projecting at right angles to the shaft 10 (preferably four in number,) one arm of which when the machine is not in operation extends upwardly to the column of pencils and serves to retain them in place in the hopper, the following arm 12' ejecting the pencil when the feeding mechanism of the machine is operated.

Rigidly secured on the shaft 10 between the star wheels 11 is a ratchet wheel 13 which is preferably composed of four teeth, the distance between the teeth corresponding to and limiting the movement of the star wheels. This ratchet wheel is engaged by a spring pressed plunger dog 14 which is mounted in a cylindrical casing 15 closed at its outer end and which contains a coiled spring 16 which serves to keep the dog 14 in engagement with the ratchet wheel 13. The plunger dog casing 15 is secured to shaft 10 by means of arms 17 which are loosely secured thereto, and has a lug 18 to which is pivotally attached a rod 19 which extends through a longitudinal slot 20 in the downwardly extending half 22 of an arm 21 which is rigidly secured to an operating shaft 23. This shaft extends transversely of the machine, the rotation of which operates the different mechanisms of the machine. To the outer end of the upwardly extending half 24 of arm 21 is secured a coiled spring 25 whose other end is secured to the frame 5 of the machine. This spring 25 keeps the downwardly extend-

- ing half of arm 21 normally in engagement with a lug 19' on rod 19, thereby returning dog 14 to its operative relation with ratchet 13. The outer end of rod 19 is bent to form 5 a stop 19'' which is engaged by the lower half of arm 21 so that when shaft 23 is rotated arm 22 contacts with stop 19'' thereby operating the ratchet mechanism connected to the feed shaft 10.
- 10 Rigidly secured to one end of the feed shaft 10 is a positioning wheel 26 having on its periphery four segmental depressions 27. This wheel contacts with a flanged wheel 28, which is mounted on the end of an arm 29 15 which is pivotally secured to the side of the frame 5. A coiled spring 30 one end of which is secured to arm 29, the other end being fastened to the frame of the machine holds wheel 28 in contact with one of the segmental 20 depressions of the positioning wheel 26, thereby bringing the star wheels to their proper position and preventing any further rotation of the feed shaft 10 at any one operation.
- 25 The location of the depressions 27 in the positioning wheel 26 are such that on the rotation of the feed shaft 10 the upper arms of each star wheel will be in position to prevent any further exit of the pencils from the 30 hopper. The projections 31 formed by the adjacent depressions in the positioning wheel when brought in contact with the flanged wheel 28 pass over the center thereof and accelerate greatly the further movement of the 35 feed shaft 10 so as to force the pencil quickly out of the hopper and against the guards 32 which are fastened to the rear of the hopper and frame of the machine.
- The coin controlled mechanism for vending 40 the articles is as follows: 40 is a coin chute which is rigidly secured to the feed hopper and which extends downwardly and terminates within a short distance of the operating shaft 23. Secured to this operating shaft is 45 a coin selective mechanism which preferably consists of a rectangular coin plate 41 rigidly secured to shaft 23, rounded on its rearwardly projecting end so as to easily discharge the coin and having in its front end a 50 rectangular notch 42 to permit of the movement of a releasing arm 43, which forms a part of a U-shaped rod 44 which is journaled in bearing 45 on the frame of the machine. Arm 46 of the U-shaped rod is bent at its 55 outer end to form a dog 47 which engages a notched disk 48 rigidly secured to the operating shaft 23 adjacent the coin plate, a coiled spring 49 holding it in positive engagement with the notched disk.
- 60 Rigidly secured to the upper side of the shaft 23 and at either side of the coin plate 41 are side plates 50 and 50' which are transversely joined by a coin guard plate 51 which has on its outer edge a notch 52 which 65 is directly over the notch in the coin plate.

The purpose of this guard plate is to prevent the coin from being thrown in the wrong direction on the operation of the machine.

Secured to the rear end of side plate 50 is a flat spring 53 which is bent at its outer 70 end to form a seat for a set screw 54, by means of which the spring 51 is moved to increase or diminish the width of the opening. Side plate 50' is secured to shaft 23 at an angle so that the space between the plates 50 and 50' is narrower at the front than at the rear, so that when a coin of the proper denomination falls from the coin chute it will be held against further movement, the tension of the spring being such as to hold it 75 firmly in place on the coin plate until the machine has completed its operation when the coin is released by the releasing arm, the coin falling into an inclined chute 55 which is secured to and leads to the coin receptacle 56 80 which is secured to the frame of the machine. If it should occur that a coin of an improper denomination or blank was inserted in the coin chute it would pass through the coin selective mechanism secured to shaft 23 to a 85 coin returning chute 57 secured to the frame 5 in front of the coin selecting mechanism and be returned to the operator.

It will be seen from the foregoing description that it will be impossible to operate the 90 device without the use of a proper coin, as the selective mechanism is so regulated that it will only stop a coin of a predetermined size.

The vending apparatus is entirely inclosed by a removable casing 70, the top of which is 100 removable so that pencils may be supplied to the hopper whenever it may become necessary. The front of the casing inclosing the hopper has an opening 71 which is closed by a glass 72 behind which an advertisement may 105 be placed. The front of the casing below the hopper extends outwardly and has an opening 73 in the downwardly inclined shelf 74 behind which an advertisement may be displayed. A coin opening 75 in the inclined shelf registers with the coin chute secured to the hopper. The casing below the inclined shelf extends downwardly and terminates a short distance from the pencil receiving tray 76, which extends outwardly a 110 short distance from the face of the case. A door 77 provided with a lock provides a means of access to the coin receptacle. An opening 78 to one side of the door 77 registers with the coin returning chute 55, and a 115 tray 79 secured to the case below the opening 78 provides means for holding the improper coins or blanks that may be returned to the operator.

The operating shaft 23 extends through 120 one side of the case and is provided with a handle 80 by means of which the mechanisms are operated. The stops 81 and 82 secured to the side of the case adjacent the handle limit the movement thereof so that 125

the different mechanisms will not be broken or disarranged.

The operation of the advice is as follows:

When a person desires to obtain a pencil, he inserts a coin of the proper denomination in the coin opening 75, the coin falling down the coin chute and on to the coin receiving plate 41 where it is held by the coin selective mechanism. The handle is then turned a short distance until the releasing arm 43 contacts with the coin on the coin plate 41, the further movement of the operating shaft 23 causes the coin to raise the releasing arm until dog 47 is disengaged from the notched disk 48. On the further movement of the operating shaft the downwardly extending arm 21 contacts with stop 19⁷ on rod 19 which operates the ratchet mechanism connected to the feed shaft thereby rotating the feed shaft and causing the arms 12' of the star wheel 11 to force a pencil out of the hopper on to the inclined chute whence it rolls downwardly to the pencil receiving tray and is delivered to the purchaser.

If a person should insert in the coin aperture a coin of improper denomination or a blank, the same will not be held by the coin selective mechanism but will pass through and into the coin returning chute 55 and be returned to the operator.

It will be seen from the foregoing description that I have produced a highly efficient machine in which the operation is positive, and at the same time will not deliver more than the proper amount of merchandise at any one operation.

Having described my invention what I claim is:

1. In a vending machine, a frame; a rotative shaft mounted in said frame; a coin selective mechanism secured to said shaft; locking means secured to said shaft and to the frame; lock-releasing means secured to said frame adapted to be actuated by the operating coin on the coin selective mechanism when the shaft is operated; said locking and lock-releasing means including a single rod pivoted in the frame, one end of which operates as a locking dog and the other end of which is positioned above the notch of the coin-retainer plate and adapted to be actuated by a coin in said coin retainer, substantially as and for the purpose specified.

coin on the coin selective mechanism as aforesaid, to move the lock-end from locking position.

2. In a vending machine, a frame; a rotative shaft mounted in said frame; a notched plate with sides secured thereto; a coin guard having a notch therein extending in a parallel plane above said notched plate and secured to the sides; a coin chute secured to the frame and terminating adjacent the notched plate; a notched disk secured to said shaft; a U-shaped rod mounted in bearings in said frame, one arm of said rod engaging the notched disk and locking the operating shaft, the other arm releasing the locking arm when brought in contact with the operating coin on the coin receiving plate; a coin returning chute secured to said frame in front of and adjacent the notched plate and terminating outside the frame; spring returning means secured to said shaft and to the frame whereby said shaft is returned to its initial position at the end of an operation; and means to rotate said shaft.

3. In a vending machine, a frame; a rotative shaft mounted in said frame; a coin selective mechanism secured to said shaft comprising a notched plate with converging sides, forming a coin-retainer, secured thereto; locking means secured to said shaft and to the frame; lock-releasing means secured to said frame adapted to be actuated by the operating coin on the coin selective mechanism when the shaft is operated; said locking and lock releasing means including a single rod pivoted in the frame, one end of which operates as a locking dog and the other end of which is positioned above the notch of the coin-retainer plate and adapted to be actuated by a coin in said coin retainer, substantially as and for the purpose specified.

In witness that I claim the foregoing I have hereunto subscribed my name this 18th day of Sept., 1906.

ARTHUR E. SMITH.
